SELF-TWILLING JACQUARD MACHINE FOR LOOMS.

Application filed July 29, 1927, Serial No. 209,248, and in Great Britain March 16, 1927.

This invention relates to self twilling jacquard machines, its object being to provide improvements therein.

With the ordinary self twilling jacquard machines, when the griffe blades in any row are inclined and the ordinary hooks are positioned above them, the twilling hooks are clear. When a peg on the twilling barrel comes into contact with its corresponding twilling bar, however, it moves the griffe blades connected therewith into the vertical position, and, on the head of the machine being raised, the rows of ordinary hooks corresponding to the said vertical griffe blades are left down, this action taking place irrespective of whether the said ordinary hooks have been left on or pushed off the griffe blades by the ordinary pattern cards. The movement of the griffe blades into the vertical plane also brings them below the twilling hooks in the rows immediately in front thereof, whereby, when the head of the machine rises as aforesaid, all the ordinary hooks in each of the said rows are lifted whether or not they are left on by the pattern cards. In an eight leaf twill, the effect of this action move the griffe blades clear of the ordinary hooks, it is ensured that one row of ordinary hooks out of every eight rows will be left down, with the result that the same proportion of warp threads selected by the pattern cards and hooks are left down also, so as to form the warp portion of the figure. On the other hand, the griffe blades, moved by the twilling bar into the vertical plane, lift the twilling hooks and thereby raise one out of every eight rows of ordinary hooks, harness and warp threads, so that this same proportion of warp is lifted from among the mass of warp threads selected by the pattern cards so as to produce the weft figure. The same sequence is repeated on the next pick of weft.

The effect of the usual twilling mechanism as above described is to produce a satisfactorily bound edge on one side of a figure but not on the other where what is known as "floating ends" are left, making an imperfect cloth.

According to the present invention, we provide a self twilling jacquard machine having primary twilling bars whereby griffe blades corresponding to any of the rows of ordinary hooks can be moved clear thereof, twilling hooks connected to cross bars where-

by the ordinary hooks are carried when not supported by the griffe blades, twilling blades, and secondary twilling bars adapted to move the twilling blades into or out of position beneath the twilling hooks. Preferably, the secondary twilling bars are independently operable by means of pegs or tappets on a rotating barrel or barrels driven by gearing from the usual tappet shaft of the jacquard machine. Eight of these independently controlled secondary twilling bars may be arranged on each side of the jacquard machine, being situated transversely of, and above, the griffe blades, and controlling as many twilling blades as there are twilling hooks on the machine. Preferably also, duplicate tappet barrels are provided at each side of the machine. The tappets can be arranged to move the twilling blades to twill the "ground" of the cloth from left to right, while the twill on the pattern is worked from right to left, or vice versa.

The secondary twilling bars, operated as described, move the required twilling blades below desired twilling hooks, so that, when the machine head rises, it will carry with it the required twilling hooks and corresponding rows of ordinary hooks to obtain the desired twilling or binding effect on the cloth.

The invention will now be described, by way of example, with reference to the accompanying drawings, whereon:

Fig. 1 is a plan view of the top portion of a "Bessbrook" self twilling jacquard machine showing the invention applied thereto;

Fig. 2 is a longitudinal elevation;

Fig. 3 is a cross sectional elevation on the line 3-3 (Fig. 1).

Referring to the drawings:

The primary twilling bars 1 (Fig. 2) have notched projections 2 on their under edge so that in known manner they can be operated for the purpose of turning the griffe blades 3 from the inclined to the vertical position, the said blades 3, when inclined, being adapted to engage the ordinary hooks 4 as the head of the machine rises. The twilling hooks 5 are adapted to be lifted by separate twilling blades 6, controlled by secondary twilling bars 7 and arranged above the twilling blades 6. The twilling bars 7 are operated by pegs or tappets 8 on barrels 9 secured on a tappet shaft 10 arranged above the usual tappet shaft 11 and driven therefrom by gearing 12. The tappets 8 can be arranged to give

independent control, as required, of each twilling bar 7 so that it is possible to lift the twilling hooks 5 and thereby any row or rows of ordinary hooks 4 in any desired order.

5 There are eight secondary twilling bars 7 on each side of the jacquard machine and the said bars 7 control as many twilling blades 6 as there are twilling hooks 5. The tappet barrels 9 at each end of the machine are shown 10 as duplicates one of the other. The tappets 8 can be arranged to move the twilling blades 6 to twill the "ground" of the cloth from left to right, while the twill on the pattern is worked from right to left, or vice versa.

13 When the tappets 8 come into contact with any one of the secondary twilling bars 7, it is pushed forward and turns the corresponding twilling blade 6 from the inclined to the vertical position, underneath the twilling hooks 5 at each side of the machine. In known manner, every ordinary hook 4 is formed at the bottom with a closed loop 14, the length of which must equal, at least, the depth of a shed. When the ordinary hooks 4 are not in action, each row thereof is supported by a bar 13 attached to the bottom of the twilling hooks 5. In Fig. 2 of the drawing, we have shown one of the ordinary hooks 4 in side elevation. When the head of the machine rises, it will carry with it the twilling hooks 5 thereby raising the bar 13 and the required row of ordinary hooks 4.

18 The twilling bars 7, operated as described, move the required twilling blades 6 below desired twilling hooks 5. For example, by referring to Figs. 1 and 2 it will be clear that the pushing over of the twilling blade 6^a by the secondary twilling bar 7 moves it into operative position below the twilling hooks 5^a. 25 When the machine head rises it will carry with it the required twilling hooks 5 and corresponding rows of ordinary hooks 4 to obtain the desired twilling or binding effect on the cloth. As shown in Figs. 1 and 2 the twilling hooks 5^a will lift the fifth row of ordinary hooks 4.

30 In an ordinary self twilling jacquard machine, the twilling hooks are lifted in the following order: first hook—fourth hook—seventh hook—second hook—fifth hook—eighth hook—third hook—sixth hook. Each of these twilling hooks lifts the row of ordinary hooks immediately behind it, and thus the order in which the rows of ordinary hooks are lifted is as follows: second row—fifth row—eighth row—third row—sixth row—first row—fourth row—seventh row.

35 This does not produce the desired binding of the cloth and, to obtain the same, we employ the means hereinbefore set forth. By this means, any of the rows of ordinary hooks can be lifted when and in the order desired. For example, we may arrange that the twilling hooks are lifted in the order above specified, that is: first hook—fourth hook—seventh

hook—second hook—fifth hook—eighth hook—third hook—sixth hook, the corresponding rows of ordinary hooks being lifted therewith, but, in contrast to the ordinary twilling motion, when the ordinary hooks in the first row are being lifted by the corresponding twilling hooks, the fifth row of ordinary hooks can be left down. Likewise, when the ordinary hooks in the fourth row are being similarly lifted, the eighth row of ordinary hooks can be left down; and so on in the following order: seventh row lifted, 70 third row left down—second row lifted, sixth row left down—fifth row lifted, first row left down—eighth row lifted, fourth row left down—third row lifted, seventh row left down—sixth row lifted, second row left down. Different twilling motions can be obtained by suitable adjustments of the primary and secondary twilling bars and the corresponding tappets. In practice, we obtain different 75 twilling or binding effects firstly by interchanging the twilling bars according to the type of twill or binding selected, and then by slackening the gear wheels on the tappet cylinders and angularly adjusting the two cylinder relatively to each other as we find necessary to make the same agree with the change made in the arrangement of the twilling bars. In some cases, of course, it is not 80 necessary to alter the arrangement of twilling bars and, when this is so, the only alteration necessary to make the same agree with the change made in the arrangement of the twilling bars. In some cases, of course, it is not 85 necessary to alter the arrangement of twilling bars and, when this is so, the only alteration necessary to make the same agree with the change made in the arrangement of the twilling bars. In some cases, of course, it is not 90 necessary to alter the arrangement of twilling bars and, when this is so, the only alteration necessary to make the same agree with the change made in the arrangement of the twilling bars. In some cases, of course, it is not 95 necessary to alter the arrangement of twilling bars and, when this is so, the only alteration necessary to make the same agree with the change made in the arrangement of the twilling bars. In some cases, of course, it is not 100 necessary to alter the arrangement of twilling bars and, when this is so, the only alteration necessary to make the same agree with the change made in the arrangement of the twilling bars. In some cases, of course, it is not 105 necessary to alter the arrangement of twilling bars and, when this is so, the only alteration necessary to make the same agree with the change made in the arrangement of the twilling bars.

The twilling mechanism described provides for separate and complete twilling for warp and weft by raising the rows of ordinary hooks en masse and as required so that loose bindings or "floating ends" which constitute the chief defect in cloth made by an ordinary self twilling machine are avoided.

110 We claim.

1. A self twilling jacquard machine having ordinary hooks arranged in rows, griffe blades for each of said rows, twilling bars engaging with said griffe blades, tappet means individual to said twilling bars for operating said griffe blades, twilling hooks, means connected to said twilling hooks for lifting rows 115 of ordinary hooks, twilling blades for each of said twilling hooks, secondary twilling bars individual to and engaging with said twilling blades, and secondary tappet means individual to said secondary twilling bars for 120 operating said twilling blades and adjustable independently of said first-mentioned tappet means.

2. A self twilling jacquard machine having ordinary hooks arranged in rows, griffe 125

blades for each of said rows, twilling bars engaging with said griffe blades, a rotatable cylinder, pinion means for rotating said cylinder, tappets on said cylinder individual to said twilling bars for operating said griffe blades, twilling hooks, means connected to said twilling hooks for lifting rows of ordinary hooks, twilling blades for each of said twilling hooks, secondary twilling bars individual to and engaging with said twilling blades, a second rotatable cylinder, pinion

means on said second cylinder adapted to engage and be angularly adjustable to said first mentioned pinion means, and secondary tappets on said second cylinder individual to 15 said secondary twilling bars for operating said twilling blades.

In testimony whereof we affix our signatures.

SAMUEL WALTER DOUGLAS.

JOHN GREGG.

MATTHEW SILCOCK.
